DERIVATIVES OF P-AMINOALKYL BENZENESULFONAMIDES

The present invention relates to new derivatives of p-aminoalkyl benzenesulfonamides, processes for their preparation, to medicaments containing the new compounds and their use.

More particularly, the present invention concerns compounds of the formula I,

wherein

R₁ is alkyl having one to six carbon atoms, allyl, cycloalkyl having five to eight carbon atoms, or cycloalkenyl having five to eight carbon atoms;

R₂ is hydrogen, ethyl or methyl;

R₃ is alkyl having one to six carbon atoms, cycloalkyl having at most eight carbon atoms, cycloalkenyl having at most eight carbon atoms, alkenyl having three to five carbon atoms or phenyl;

R₄ is hydrogen, alkyl having one to six carbon atoms, or phenyl; and

R₃ and R₄ together are a polymethylene chain having four to seven carbon atoms, which can be interrupted by an oxygen atom;

X is oxygen or sulfur; and

m is 2 or 3;

and the pharmaceutically acceptable acid addition salts thereof, which compounds have a hypoglycemic action in warm-blooded animals.

In the compounds of formula I, R₁ may have, e.g. the following meanings:

as alkyl, R₁ can denote methyl, ethyl, propyl isopropyl, butyl, sec.butyl, tert.butyl, isobutyl, pentyl, isopentyl, 2,2-dimethylpropyl, 1-methylbutyl, 1-ethylpropyl, 1,2 dimethylpropyl, n-hexyl, methylpentyl, dimethylbutyl, or ethylbutyl; as cycloalkyl, R₁ can denote cyclopentyl, which can be optionally substituted by alkyl having one-three carbon atoms; cyclohexyl, which can be substituted by ethyl or methyl; cycloheptyl, optionally substituted by methyl; as well as cyclooctyl; as cycloalkenyl, R₁ can denote 2-cyclopenten-1-yl, 2-cyclohexen-1-yl, 3-cyclohexen-1-yl, 2-methyl-2-cyclohexen-1-yl, 3-cyclohepten-1-yl, or a cyclooctenyl group.

The substituent R₃ embraces the same alkyl, cycloalkyl or cycloalkenyl groups as stated under R₁; as alkenyl, R₃ can denote allyl, 1-methylallyl, 2-methylallyl, 2- or 3-butenyl, or 2-, 3- or 4-pentenyl.

Compounds of formula I are produced by reacting a compound of formula II,

wherein

R₁, R₂ and m have the meaning given under formula I, with an isocyanate of formula III,

(III)

wherein

R₃ and X have the meaning given under formula I; or with a reactive derivative of a carbamic acid or thiocarbamic acid of formula IV,

wherein

R₃, R₄ and X have the meaning given under formula I; and, optionally, converting the obtained reaction products into the salt of an inorganic or organic acid.

Suitable as reactive derivatives of a carbamic acid or thiocarbamic acid of formula III are, e.g. the halides, especially the chlorides, the lower alkyl esters, particularly the methyl or ethyl esters, the phenyl esters, the amides, the lower mono- or dialkylamides, in particular the N-methyl amides and the N,N-dimethylamides, the diphenylamides, also the N-acylamides such as, e.g. the acetyl amides and the benzoylamides.

The reaction is performed, e.g. at room temperature, or by heating in an inert organic solvent. Suitable as such are, e.g. hydrocarbons such as benzene, toluene or xylene, ethers such as diethyl ether, dioxane or tetrahydrofuran, chlorinated hydrocarbons such as methylene chloride, and lower ketones such as acetone or methyl ethyl ketone. The reaction can, in general, be carried out without the addition of condensing agents; optionally, however, such agents, e.g. alkali metal alkoholates and alkali metal hydroxides, can be added.

A halide of a carbamic acid or thiocarbamic acid of formula IV is reacted according to the invention, preferably in the presence of an acid binding agent. As such it is possible to use inorganic bases or salts, such as, e.g. an alkali hydroxide, alkali acetate, alkali hydrogen carbonate, alkali carbonate and alkali phosphate, such as sodium hydroxide, sodium acetate, sodium hydrogen carbonate, sodium carbonate and sodium phosphate, or the corresponding potassium compounds. It is also possible to use calcium oxide, calcium carbonate, as well as calcium phosphate and magnesium carbonate. In addition to inorganic bases or salts, organic bases are also suitable such as, e.g. pyridine, trimethyl- or triethylamine, diisopropylamine, or collidine. Added in excess, these can also be used as solvent.

Instead of amines of formula II, it is also possible to use for the reaction (according to the invention) with a carbamic or thiocarbamic acid chloride, N-alkali metal derivatives of these compounds, such as e.g. sodium, potassium or lithium derivatives.

The starting compounds of formula II are, for their part, new compounds. They can be produced, e.g. by reacting a reactive derivative of a sulfonic acid of formula V.

wherein

R is a simple alkyl or aryl, e.g. methyl or phenyl, and m has the meaning given in formula I, with 2-amino-2-imidazoline derivatives of the formula VI,

wherein

R₁ and R₂ have the meaning given under formula I; and afterwards hydrolytically splitting-off the protective acyl group (R—CO—). The N-acyl compounds derived from formula II, obtained as intermediate product, have likewise not been described hitherto in the literature.

Suitable reactive derivatives of a sulfonic acid of formula V are halides, especially chlorides and anhydrides of formula Va,

wherein R has the meaning given under formula V. The anhydrides of formula Va can be obtained in a simple manner by the reaction of corresponding substituted sulfonic acid halides with salts of correspondingly substituted sulfonic acids.

Using a further process, starting materials of formula II are obtained by reacting substituted p-(aminoalkyl)-benzenesulfonamides of formula VII,

wherein m has the meaning given under formula I, with substituted N-(2-bromoalkyl)-cyanoamides in an alkaline medium. Compounds of formula VII are, in turn, obtained substantially in accord with E. Miller, et al., J. Am. Chem. Soc., 62,2099 (1940). Thus, for example, N-acetylphenethylamine is reacted with chlorosulfonic acid. The resulting sulfonylchloride is converted to the corresponding sulfonamide with aqueous ammonia and finally, the acetyl group is hydrolyzed to give the p-(β -aminoethyl)-benzenesulfonamide.

The preparation of the starting compounds of formula III and of formula IV is carried out using the generally known preparation methods for isocyanates, and carbamic acid derivatives and thiocarbamic acid derivatives, respectively.

Pharmaceutically acceptable salts comprised by the present invention are readily available by allowing to reach a compound of formula I with a suitable acid and isolating the salt by conventional methods.

For formation of pharmaceutically acceptable salts it is possible to use physiologically harmless inorganic or organic acids, such as, e.g. hydrochloric acid, hydrobromic acid, sulfuric acid, phosphoric acid, methanesulfonic acid, acetic acid, lactic acid, succinic acid, tartaric acid and maleic acid. Also hypoglycemic sulfonyl ureas such as, e.g. p-toluene-sulfonylbutyl urea, p-chlorobenzenesulfonylpropyl urea, and p[2-(2-methoxy-5-chlorobenzamido)-ethyl]-phenylsulfonylcyclohexyl urea can be used.

The compounds of the present invention have been found to have valuable hypoglycemic activities in warm-blooded animals upon oral or parenteral administration. These activities are illustratively demonstrated in rats by orally administering the test com-

ound to groups of five to six animals which have not been fed for 24 hours. Blood samples are taken from the vein, and the blood sugar content is determined according to the method of Hagedorn-Jenson with an auto-analyzer. Thus, it is shown that 1-[p-(2-(3-n-butyl-2-thioureido)-ethyl)-phenylsulfonyl]-2-imino-3-n-butyl-imidazolidine on oral administration in amounts from about 20 to about 400 mg/kg of bodyweight has a pronounced blood sugar lowering effect.

Similar effects are found with other compounds of the invention.

The compounds of formula I and the pharmaceutically acceptable salts thereof, are preferably administered orally in a daily dosage of from 10 to 400 mg/kg of bodyweight. The dosage must necessarily be adjusted to the age, size and condition of the particular host being treated.

For their intended use the compounds of the invention are provided in dosage unit forms including for example, tablets, capsules, dragees, powders, syrups, elixirs, and the like.

Suitable dosage units such as dragees or tablets, preferably contain 10-200 mg of an active substance according to the invention, whereby the content of active substance is 20-80 percent by weight. Tablets and dragees are produced by combining the active substance, e.g. with solid pulverulent carriers such as lactose, saccharose, sorbitol or mannitol; starches such as potato starch, maize starch or amylopectin, also laminaria powder or citrus pulp powder, cellulose derivatives or gelatine, optionally with the addition of lubricants, such as magnesium or calcium stearate or polyethylene glycols of suitable molecular weights. The tablets and dragee-cores are coated, e.g. with concentrated sugar solutions which may also contain, e.g. gum arabic, talcum and/or titanium dioxide; or with a lacquer dissolved in readily volatile organic solvents or mixtures of solvents. Dyestuffs can be added to these coatings, e.g. to distinguish between varying dosages of active substance.

Other suitable dosage units for oral administration are hard gelatin capsules, as well as soft closed capsules made from gelatine and a softener such as glycerin. The hard capsules preferably contain the active substance as a granulate, e.g. in admixture with fillers such as maize starch, and/or lubricants such as talcum or magnesium stearate and, optionally, stabilizers such as sodium metabisulfite (Na₂S₂O₅) or ascorbic acid. In soft capsules, the active substance is n-propylisocyanate, dissolved or suspended in suitable liquids such as liquid polyethylene glycols, whereby stabilizers may also be added.

The following examples will serve to further typify the nature of the present invention, but should not be construed as a limitation on the scope thereof. Temperatures are given in degrees Centigrade.

EXAMPLE 1

a. An amount of 39.8 g of 1-[p-(2-aminoethyl)-phenylsulphonyl]-2-imino-3-n-butyl-imidazolidinedihydrochloride is dissolved in 100 ml of water, and the base liberated with 150 ml of 2-n sodium hydroxide solution. It is extracted with 3 times 250 ml of methylene chloride. To the methylene chloride solu-

tion (dried with sodium sulphate) are added 8.5 g of n-propylisocynate, and stirring is maintained for 1 hour. The reaction mixture is then concentrated in vacuo, and the crystalline residue recrystallized from ethyl acetate. 1-[p-(2-(3-n-propylureido)-ethyl)-phenylsulphonyl]-2-imino-3-n-butyl-imidazolidine melts at 164°-166°.

b. The starting material: 1-[p-(2-aminoethyl)-phenylsulphonyl]-2-imino-3-butyl-imidazolidinedihydrochloride, is obtained by two processes:

1. An amount of 36.65 g of 1-[p-(2-acetaminoethyl)-phenylsulphonyl]-2-imino-3-butyl-imidazolidine is dissolved in 370 ml of 2-n hydrochloric acid, and the solution refluxed for 6 hours. The solution is then concentrated to dryness in vacuo, and the obtained oil dissolved in alcohol. The 1-[p-(2-aminoethyl)-phenylsulphonyl]-2-imino-3-butyl-imidazolidinedihydrochloride crystallizes out in the cold state, M.P. 231°-233°. **dissolved**

1-[p-(2-Acetamidoethyl)-phenylsulphonyl]-2-imino-3-butyl-imidazolidine can be produced as follows:

To a solution of 8.5 g of sodium hydroxide in 85 ml of water are added 17.8 g of 1-butyl-2-iminoimidazolidine-hydrochloride. To the obtained clear solution is added a solution of 26.6 g of p-(2-acetamidoethyl)-benzenesulphochloride in 100 ml of acetone, whereby a rise in temperature occurs. The mixture is subsequently heated for half an hour to 90°, and then concentrated to dryness in vacuo. The residue is recrystallized from ethyl acetate. The pure 1-[p-(2-acetamidoethyl)-phenylsulphonyl]-2-imino-3-butyl-imidazolidine melts at 130°-131°.

The 1-[p-(2-acetamidoethyl)-phenylsulphonyl]-2-imino-imidazolidines required in the following examples for the production of the starting material are obtained in an analogous manner, by the reaction of p-(2-acetamidoethyl)-benzenesulphochloride with correspondingly substituted 2-imino-imidazolidines. 2. A mixture of 100 ml of dimethylsulphoxide, 11.2 g of powdered potassium hydroxide, 23.65 g of p-(2-aminoethyl)-benzenesulphonamide hydrochloride [Lit.: E. Miller et al., J. Amer. Chem. Soc. 62, 2101, (1940)] and 16 g of N-(2-chloroethyl)-N-butylcyanimide is heated, whilst being stirred, for 1 hour in an oil bath at 110°. After cooling, the mixture is poured on to water. The obtained cloudy solution is rendered alkaline with concentrated sodium hydroxide solution, saturated with sodium chloride, and extracted three times with methylene chloride; the organic phases are dried over sodium sulphate, filtered and concentrated by evaporation. The obtained oil (free base) is **DIS-SOLVED** in alcohol, and made acidic with saturated alcoholic hydrochloric acid. As a result of cooling and, if necessary, dilution with ether, 1-[p-(2-aminoethyl)-phenylsulphonyl]-2-imino-3-butyl-imidazolidine dihydrochloride precipitates, M.P. 231°-233°.

EXAMPLE 2

In an analogous manner to Example 1 are obtained: from 38.4 g of 1-[p-(2-aminoethyl)-phenylsulphonyl]-2-imino-3-isopropyl-imidazolidine-dihydrochloride and 12.5 g of cyclohexyl-isocyanate the 1-[p-(2-(cyclohexyl-ureido)-ethyl)-phenylsulphonyl]-2-imino-3-isopropyl-imidazolidine, M.P. 158°-158°.

from 42.5 g of 1-[p-(2-amino-ethyl)-phenylsulphonyl]-2-imino-3-n-butyl-4-ethyl-imidazolidine-dihydrochloride and 12.5 g of cyclohexyl-isocyanate the 1-[p-(2-(cyclohexyl-ureido)-ethyl)-phenylsulphonyl]-2-imino-3-n-butyl-4-ethyl-imidazolidine, M.P. 98°-99°.

from 43.7 g of 1-[p-(2-amino-propyl)-phenylsulphonyl]-2-imino-3-cyclohexyl-imidazolidine-dihydrochloride and 12.5 g cyclohexyl-isocyanate the 1-[p-(2-(cyclohexyl-ureido)-propyl)-phenylsulphonyl]-2-imino-3-cyclohexyl-imidazolidine, M.P. 201°-202°.

EXAMPLE 3

Starting with 39.8 g of 1-[p-(2-aminoethyl)-phenylsulphonyl]-2-imino-3-n-butyl-imidazolidine-dihydrochloride are obtained, analogously to Example 1, the following:

a. with 8.5 g of isopropylisocyanate, 1-[p-(2-(3-isopropylureido)-ethyl)-phenylsulphonyl]-2-imino-3-n-butyl-imidazolidine, M.P. 151°-152° (from ethyl acetate);

b. with 9.9 g of n-butylisocyanate, 1-[p-(2-(3-n-butylylureido)-ethyl)-phenylsulphonyl]-2-imino-3-n-butyl-imidazolidine, M.P. 158°-159° (from ethyl acetate);

c. with 11.5 g of n-butyliothiocyanate, 1-[p-(2-(3-n-butyl-2-thioureido)-ethyl)-phenylsulphonyl]-2-imino-3-n-butyl-imidazolidine, M.P. 183°-184° (from ethyl acetate);

d. with 11.1 g of cyclopentylisocyanate, 1-[p-(2-(3-cyclopentylureido)-ethyl)-phenylsulphonyl]-2-imino-3-n-butyl-imidazolidine, M.P. 176°-177° (from ethyl acetate);

e. with 11.9 g of phenylisocyanate, 1-[p-(2-(3-phenylureido)-ethyl)-phenylsulphonyl]-2-imino-3-n-butyl-imidazolidine hemihydrate, M.P. 210°-211° (from ethyl acetate);

f. with 13.5 g of phenylisothiocyanate, 1-[p-(2-(3-phenyl-2-thioureido)-ethyl)-phenylsulphonyl]-2-imino-3-n-butyl-imidazolidine containing one-fourth mole of hydrogen, M.P. 195°-196° (from ethyl acetate);

EXAMPLE 4

a. 38.4 g of 1-[p-(2-aminoethyl)-phenylsulphonyl]-2-imino-3-n-propyl-imidazolidine dihydrochloride are dissolved in 100 ml of water; and the base is liberated with 150 ml of 2-n sodium hydroxide solution. It is extracted with 3 times 250 ml of methylene chloride. To the methylene chloride solution (dried with sodium sulphate) are added 12.5 g of cyclohexylisocyanate, and stirring is maintained for 1 hour. The reaction mixture is then concentrated in vacuo, and the crystalline residue recrystallized from ethyl acetate. The 1-[p-(2-(3-cyclohexylureido)-ethyl)-phenylsulphonyl]-2-imino-3-n-propyl-imidazolidine melts at 185°-186°.

b. The starting material: 1-[p-(2-aminoethyl)-phenylsulphonyl]-2-imino-3-propyl-imidazolidine dihydrochloride, is produced by two processes:

1. An amount of 35.2 g of 1-[p-(2-acetaminoethyl)-phenylsulphonyl]-2-imino-3-propyl-imidazolidine is dissolved in 370 ml of 2-n hydrochloric acid, and the solution refluxed for 6 hours. The solution is then concentrated to dryness in vacuo, and the obtained oil dissolved in alcohol. The 1-[p-(2-aminoethyl)-

benzenesulphonyl]-2-imino-3-propyl-imidazolidine dihydrochloride, M.P. 255°-256°, crystallizes out in the cold state. 2. A mixture of 100 ml of dimethylsulphoxide, 11.2 g of powdered potassium hydroxide, 23.65 g of p-(2-aminoethyl)-phenylsulphonamide hydrochloride [Lit.: E.Miller et al. J.Amer.Chem.Soc.62, 2101, (1940)] and 16 g of N-(2-chloroethyl)-N-propyl-cyanamide is heated, whilst being stirred, for 1 hour in an oil-bath at 110°. After the mixture has cooled, it is poured on to water. The obtained cloudy solution is rendered alkaline with concentrated sodium hydroxide solution, saturated with sodium chloride, and extracted three times with methylene chloride; the organic phases are dried over sodium sulphate, filtered and concentrated by evaporation. The obtained oil (free base) is dissolved in alcohol, and made acid with saturated alcoholic hydrochloric acid. As a result of cooling and, if necessary, dilution with ether, 1-[p-(2-aminoethyl)-phenylsulphonyl]-2-imino-3-propyl-imidazolidine dihydrochloride, M.P. 255°-256°, precipitates.

EXAMPLE 5

a. 39.8 g of 1-[p-(2-aminoethyl)-phenylsulphonyl]-2-imino-3-isobutyl-imidazolidine dihydrochloride are dissolved in 100 ml of water, and the base liberated with 150 ml of 2-n sodium hydroxide solution. It is extracted with 3 times 250 ml of methylene chloride. To the methylene chloride solution (dried with sodium sulphate) are added 8.5 g of n-propylisocyanate, and stirring is maintained for 1 hour. The reaction mixture is then concentrated in vacuo, and the crystalline residue recrystallized from ethyl acetate. The 1-[p-(2-(3-n-propylureido)-ethyl)-phenylsulphonyl]-2-imino-3-isobutyl-imidazolidine melts at 154°-156°.

b. The starting material: 1-[p-(2-aminoethyl)-phenylsulphonyl]-2-imino-3-isobutyl-imidazolidine-dihydrochloride monohydrate, is produced by two processes:

1. An amount of 36.65 g of 1-[p-(2-acetaminoethyl)-phenylsulphonyl]-2-imino-3-isobutyl-imidazolidine is dissolved in 370 ml of 2-n. hydrochloric acid, and the solution is refluxed for 6 hours. The solution is then concentrated to dryness in vacuo, and the obtained oil dissolved in alcohol. The 1-[p-(2-aminoethyl)-benzenesulphonyl]-2-imino-3-isobutyl-imidazolidine-dihydrochloride monohydrate, M.P. 151-152, crystallizes out in the cold state.

2. A mixture of 100 ml of dimethylsulphoxide, 11.2 g of powdered potassium hydroxide, 23.65 g of p-(2-aminoethyl)-benzenesulphonamide hydrochloride [Lit.: E.Miller et al. J.Amer.Chem.Soc. 62, 2101, (1940)] and 20.5 g of N-(2-bromoethyl)-N-isobutyl-cyanamide is heated, whilst being stirred, for 1 hour in an oil-bath at 110°. After the mixture has cooled, it is poured on to water. The obtained cloudy solution is made alkaline with concentrated sodium hydroxide solution, saturated with sodium chloride, and extracted three times with methylene chloride; the organic phases are dried over sodium sulphate, filtered and concentrated by evaporation. The obtained oil (free base) is dissolved in alcohol and made acid with saturated alcoholic hydrochloric acid. As a result of cooling and, if necessary, dilution with ether, 1-[p-(2-aminoethyl)-phenylsulphonyl]-2-imino-3-isobutyl-

imidazolidine-dihydrochloride monohydrate, M.P. 151°-152°, precipitates.

EXAMPLE 6

5 In an analogous manner to Example 4 is obtained, starting with 39.8 g of 1-[p-(2-aminoethyl)-phenylsulphonyl]-2-imino-3-isobutyl-imidazolidine-dihydrochloride with 12.5 g of cyclohexylisocyanate, 1-[p-(2-(3-cyclohexylureido)-ethyl)-phenylsulphonyl]-2-imino-3-isobutyl-imidazolidine, M.P. 171°-172.5° (from acetyl acetate).

EXAMPLE 7

15 a. 41.0 g of 1-[p-(2-aminoethyl)-phenylsulphonyl]-2-imino-3-cyclopentyl-imidazolidine-dihydrochloride are dissolved in 100 ml of water, and the base is liberated with 150 ml of 2-n sodium hydroxide solution. The base is extracted with 3 times 250 ml of methylene chloride. To the methylene chloride solution (dried with sodium sulphate) are added 5.7 g of methylisocyanate, and stirring is maintained for 1 hour. The reaction mixture is then concentrated in vacuo, and the crystalline residue recrystallized from ethyl acetate. 1-[p-(2-(3-methylureido)-ethyl)-phenylsulphonyl]-2-imino-3-cyclopentyl-imidazolidine melts at 129°-130°.

b. The starting material: 1-[p-(2-aminoethyl)-phenylsulphonyl]-2-imino-3-cyclopentyl-imidazolidine-dihydrochloride, is obtained by two processes:

25 1. An amount of 37.8 g of 1-[p-(2-acetaminoethyl)-phenylsulphonyl]-2-imino-3-cyclopentyl-imidazolidine is dissolved in 370 ml of 2-n hydrochloric acid, and the solution is refluxed for 6 hours. The solution is then concentrated to dryness in vacuo, and the obtained oil dissolved in alcohol. The 1-[p-(2-aminoethyl)-benzenesulphonyl]-2-imino-3-cyclopentyl-imidazolidine-dihydrochloride, M.P. 270°, crystallizes out in the cold state.

30 2. A mixture of 100 ml of dimethylsulphoxide, 11.2 g of powdered potassium hydroxide, 23.65 g of p-(2-aminoethyl)-phenylsulphonamide-hydrochloride [Lit.: E.Miller et al. J.Amer.Chem.Soc. 62, 2101, (1940)] and 17.2 g of N-(2-chloroethyl)-N-cyclopentyl-cyanamide is heated, whilst being stirred, for 1 hour in an oil bath at 110°. After the mixture has cooled, it is poured on to water. The obtained cloudy solution is made alkaline with concentrated sodium hydroxide solution,

35 saturated with sodium chloride, and extracted three times with methylene chloride; the organic phases are dried over sodium sulphate, filtered and concentrated by evaporation. The obtained oil (free base) is dissolved in alcohol, and made acid with saturated al-

40 coholic hydrochloric acid. As a result of cooling and, if necessary, dilution with ether, 1-[p-(2-aminoethyl)-benzenesulphonyl]-2-imino-3-cyclopentyl-imidazolidine-dihydrochloride, M.P. 270°, (decom-

45 position) precipitates.

50 55 60 65 60

EXAMPLE 8

Analogously to Example 7 is obtained, starting with 41.0 g of 1-[p-(2-aminoethyl)-phenylsulphonyl]-2-imino-3-cyclopentyl-imidazolidine-dihydrochloride, the following:

a. with 9.9 g of n-butylisocyanate, 1-[p-(2-(3-n-butylureido)-ethyl)-phenylsulphonyl]-2-imino-3-

cyclopentyl-imidazolidine, M.P. 134°-136° (from ethyl acetate).

EXAMPLE 9

a. 42.4 g of 1-[p-(2-aminoethyl)-phenylsulphonyl]-2-imino-3-cyclohexyl-imidazolidine-dihydrochloride are dissolved in 100 ml of water, and the base is liberated with 150 ml of 2-n sodium hydroxide solution. The base is extracted with 3 times 250 ml of methylene chloride. To the methylene chloride solution (dried with sodium sulphate) are added 9.9 g of n-butyliocyanate, and stirring is maintained for one hour. The reaction mixture is then concentrated in vacuo, and the crystalline residue recrystallized from ethyl acetate. 1-[p-(2-(3-n-butyureido)-ethyl)-phenylsulphonyl]-2-imino-3-cyclohexyl-imidazolidine melts at 161.5°-162°.

b. The starting material: 1-[p-(2-aminoethyl)-phenylsulphonyl]-2-imino-3-cyclohexyl-imidazolidine-dihydrochloride, is obtained by two processes:

1. An amount of 39.2 g of 1-[p-(2-acetaminoethyl)-phenylsulphonyl]-2-imino-3-cyclohexyl-imidazolidine is dissolved in 370 ml of 2-n hydrochloric acid, and the solution is refluxed for 6 hours. The solution is then concentrated to dryness in vacuo, and the obtained oil dissolved in alcohol. The 1-[p-(2-aminoethyl)-phenylsulphonyl]-2-imino-3-cyclohexyl-imidazolidine-dihydrochloride, M.P. 247°-250°, crystallises out in the cold state. 2. A mixture of 100 ml of dimethylsulphoxide, 11.2 g of powdered potassium hydroxide, 23.65 g of p-(2-aminoethyl)-benzenesulphonamide hydrochloride [Lit.: E. Miller et al, J. Amer. Chem. Soc. 62, 2101, (1940)] and 23.1 g of N-(2-bromoethyl)-N-cyclohexylcyanamide is heated, whilst being stirred, for 1 hour in an oil-bath at 110°. After the mixture has cooled, it is poured on to water. The obtained cloudy solution is made alkaline with concentrated sodium hydroxide solution, saturated with sodium chloride, and extracted three times with methylene chloride; the organic phases are dried over sodium sulphate, filtered and concentrated by evaporation. The obtained oil (free base) is dissolved in alcohol, and made acid with saturated alcoholic hydrochloric acid. As a result of cooling and, if necessary, dilution with ether, 1-[p-(2-aminoethyl)-phenylsulphonyl]-2-imino-3-cyclohexyl-imidazolidine-dihydrochloride, M.P. 247°-250°, precipitates.

EXAMPLE 10

Starting with 42.4 g of 1-[p-(2-aminoethyl)-phenylsulphonyl]-2-imino-3-cyclohexyl-imidazolidine-dihydrochloride, the following are obtained analogously to Example 9:

a. with 11.5 g of n-butyliothiocyanate, 1-[p-(2-(3-n-butyl-2-thioureido)-ethyl)-phenylsulphonyl]-2-imino-3-cyclohexyl-imidazolidine, M.P. 186°-187° (from ethyl acetate);

b. with 11.9 g of phenylisocyanate, 1-[p-(2-(3-phenyl-2-thioureido)-ethyl)-phenylsulphonyl]-2-imino-3-cyclohexyl-imidazolidine, M.P. 210.5°-212° (from ethyl acetate);

c. with 13.5 g of phenylisothiocyanate, 1-[p-(2-(3-phenyl-2-thioureido)-ethyl)-phenylsulphonyl]-2-imino-3-cyclohexyl-imidazolidine, M.P. 188°-189° (from ethyl acetate).

EXAMPLE 11

43.8 g of 1-[p-(2-aminoethyl)-phenylsulphonyl]-2-imino-3-(4-methylcyclohexyl)-imidazolidine-dihydrochloride are dissolved in 100 ml of water, and the base is liberated with 150 ml of 2-n sodium hydroxide solution. It is extracted with 3 times 250 ml of methylene chloride. To the methylene chloride solution (dried with sodium sulphate) are added 8.5 g of n-propyl-isocyanate, and stirring proceeds for one hour. The reaction mixture is thereupon concentrated in vacuo, and the crystalline residue recrystallized from ethyl acetate. The 1-[p-(2-(3-n-propylureido)-ethyl)-phenylsulphonyl]-2-imino-3-(4-methylcyclohexyl)-imidazolidine, containing one-fourth mole of water, melts at 162.5°-163°.

The starting material: 1-[p-(2-aminoethyl)-benzenesulphonyl]-2-imino-3-(4-methylcyclohexyl)-imidazolidine-dihydrochloride is obtained by two processes:

a. An amount of 40.7 g of 1-[p-(2-acetaminoethyl)-phenylsulphonyl]-2-imino-3-(4-methylcyclohexyl)-imidazolidine is dissolved in 370 ml of 2-n hydrochloric acid, and the solution refluxed for 6 hours. The solution is then concentrated to dryness in vacuo, and the obtained oil dissolved in alcohol. The 1-[p-(2-aminoethyl)-benzenesulphonyl]-2-imino-3-(4-methylcyclohexyl)-imidazolidine-dihydrochloride, M.P. 260°, (with decomposition), crystallises out in the cold state.

b. A mixture of 100 ml of dimethylsulphoxide, 11.2 g of powdered potassium hydroxide, 23.65 g of p-(2-aminoethyl)-benzenesulphonamide-hydrochloride [Lit.: E. Miller et al, J. Amer. Chem. Soc. 62, 2101, (1940)] and 200 g of 2-chloroethyl-(4-methylcyclohexyl)-cyanamide is heated, whilst being stirred, for 1 hour in an oil-bath at 110°. After the mixture has cooled, it is poured on to water. The obtained cloudy solution is made alkaline with concentrated sodium hydroxide solution, saturated with sodium chloride, and extracted three times with methylene chloride; the organic phases are dried over sodium sulphate, filtered, and concentrated by evaporation. The obtained oil (free base) is dissolved in alcohol, and made acid with saturated alcoholic hydrochloric acid. As a result of cooling and, if necessary, dilution with ether, 1-[p-(2-aminoethyl)-benzenesulphonyl]-2-imino-3-(4-methylcyclohexyl)-imidazolidine-dihydrochloride, M.P. 260° (with decomposition) precipitates.

EXAMPLE 12

Starting with 49.8 g of 1-[p-(2-aminoethyl)-phenylsulphonyl]-2-imino-3-(4-methylcyclohexyl)-imidazolidine-dihydrochloride, the following are obtained analogously to Example 11:

a. with 11.5 g of n-butyliothiocyanate, 1-[p-(2-(3-n-butyl-2-thioureido)-ethyl)-phenylsulphonyl]-2-imino-3-(4-methylcyclohexyl)-imidazolidine, M.P. 170°-171° (from ethyl acetate);

b. with 12.5 g of cyclohexylisocyanate, 1-[p-(2-(3-cyclohexylureido)-ethyl)-phenylsulphonyl]-2-imino-3-(4-methylcyclohexyl)-imidazolidine, M.P. 179°-182° (from ethyl acetate);

c. with 11.9 g of phenylisocyanate, 1-[p-(2-(3-phenyl-2-thioureido)-ethyl)-phenylsulphonyl]-2-imino-3-(4-methylcyclohexyl)-imidazolidine, M.P. 213°-214° (from ethyl acetate);

d. with 13.5 g of phenylisothiocyanate, 1-[p-(2-(3-phenyl-2-thioureido)-ethyl)-phenylsulphonyl]-2-imino-3-(4-methylcyclohexyl)-imidazolidine, M.P. 181.5° - 182.5° (from ethyl acetate).

EXAMPLE 13

Analogously to Example 11 are obtained:

from 42.3 g of 1-[p-(2-amino-ethyl)-phenylsulphonyl]-2-imino-3-cyclohexyl-imidazolidine-dihydrochloride and 7.7 g of ethyl-isothiocyanate the 1-[p-(2-(3-ethyl-2-thioureido)-ethyl)-phenylsulphonyl]-2-imino-3-cyclohexyl-imidazolidine, M.P. 140°.

from 42.3 g of 1-[p-(2-amino-ethyl)-phenylsulphonyl]-2-imino-3-cyclohexyl-imidazolidine-dihydrochloride and 7.3 g of methyl-isothiocyanate the 1-[p-(2-(3-methyl-2-thioureido)-ethyl)-phenylsulphonyl]-2-imino-3-cyclohexyl-imidazolidine, M.P. 187° - 188°.

from 40.9 g 1-[p-(2-amino-ethyl)-phenylsulphonyl]-2-imino-3-cyclopentyl-imidazolidine-dihydrochloride and 7.7 g of ethyl-isothiocyanate the 1-[p-(2-(3-ethyl-2-thioureido)-ethyl)-phenylsulphonyl]-2-imino-3-cyclopentyl-imidazolidine, M.P. 178°.

from 40.9 g 1-[p-(2-amino-ethyl)-phenylsulphonyl]-2-imino-3-cyclopentyl-imidazolidine-dihydrochloride and 7.3 g of methyl-isothiocyanate the 1-[p-(2-(3-methyl-2-thioureido)-ethyl)-phenylsulphonyl]-2-imino-3-cyclopentyl-imidazolidine, M.P. 179°.

from 39.7 g of 1-[p-(2-amino-ethyl)-phenylsulphonyl]-2-imino-3-n-butyl-imidazolidine-dihydrochloride and 13.7 g of cyclopentyl-isothiocyanate the 1-[p-(2-(3-cyclopentyl-2-thioureido)-ethyl)-phenylsulphonyl]-2-imino-3-n-butyl-imidazolidine, M.P. 206° - 207°.

from 35.5 g of 1-[p-(2-amino-ethyl)-phenylsulphonyl]-2-imino-3-methyl-imidazolidine-dihydrochloride and 11.5 g of n-butyl-isothiocyanate the 1-[p-(2-(3-n-butyl-2-thioureido)-ethyl)-phenylsulphonyl]-2-imino-3-methyl-imidazolidine, M.P. 174.5° - 176°.

from 38.1 g of 1-[p-(2-amino-ethyl)-phenylsulphonyl]-2-imino-3-allyl-imidazolidine-dihydrochloride and 11.5 g n-Butyl-isothiocyanate the 1-[p-(2-(3-n-butyl-2-thioureido)-ethyl)-phenylsulphonyl]-2-imino-3-allyl-imidazolidine, M.P.

from 42.5 g 1-[p-(2-amino-ethyl)-phenylsulphonyl]-2-imino-3-(1,2-dimethyl-butyl)-imidazolidine-dihydrochloride and 8.7 g of ethyl-isothiocyanate the 1-[p-(2-(3-ethyl-2-thioureido)-ethyl)-phenylsulphonyl]-2-imino-3-(1,2-dimethyl-butyl)-imidazolidine, M.P. 122.5° - 124°.

from 40.9 g of 1-[p-(2-amino-ethyl)-phenylsulphonyl]-2-imino-3-cyclopentyl-imidazolidine-dihydrochloride and 10.1 g of n-propyl-isothiocyanate the 1-[p-(2-(3-n-propyl-2-thioureido)-ethyl)-phenylsulphonyl]-2-imino-3-cyclopentyl-imidazolidine, M.P. 184.5° - 185°.

from 40.9 g of 1-[p-(2-amino-ethyl)-phenylsulphonyl]-2-imino-3-cyclopentyl-imidazolidine-dihydrochloride and 10.1 g of isopropyl-isothiocyanate the 1-[p-(2-(3-isopropyl-2-thioureido)-ethyl)-phenylsulphonyl]-2-imino-3-cyclopentyl-imidazolidine, M.P. 196° - 197°.

from 40.9 g of 1-[p-(2-amino-ethyl)-phenylsulphonyl]-2-imino-3-cyclopentyl-imidazolidine-dihydrochloride and 11.5 g of n-butyl-isothiocyanate the 1-[p-(2-(3-n-butyl-2-thioureido)-ethyl)-phenylsulphonyl]-2-imino-3-cyclopentyl-imidazolidine, M.P. 179° - 180°.

from 40.9 g of 1-[p-(2-amino-ethyl)-phenylsulphonyl]-2-imino-3-cyclopentyl-imidazolidine-dihydrochloride

and 11.5 g of sec. butyl-isothiocyanate the 1-[p-(2-(3-sec.butyl-2-thioureido)-ethyl)-phenylsulphonyl]-2-imino-3-cyclopentyl-imidazolidine, M.P. 191° - 192°.

from 40.9 g of 1-[p-(2-amino-ethyl)-phenylsulphonyl]-2-imino-3-cyclopentyl-imidazolidine-dihydrochloride and 11.5 g of tert.butyl-isothiocyanate the 1-[p-(2-(3-tert.butyl-2-thioureido)-ethyl)-phenylsulphonyl]-2-imino-3-cyclopentyl-imidazolidine, M.P. 190° - 191° (decomposition).

from 40.9 g of 1-[p-(2-amino-ethyl)-phenylsulphonyl]-2-imino-3-cyclopentyl-imidazolidine-dihydrochloride and 12.9 g of isopentyl-isothiocyanate the 1-[p-(2-(3-isopentyl-2-thioureido)-ethyl)-phenylsulphonyl]-2-imino-3-cyclopentyl-imidazolidine, M.P.

from 42.3 g of 1-[p-(2-amino-ethyl)-phenylsulphonyl]-2-imino-3-cyclohexyl-imidazolidine-dihydrochloride and 10.1 g of n-propyl-isothiocyanate the 1-[p-(2-(3-n-propyl-2-thioureido)-ethyl)-phenylsulphonyl]-2-imino-3-cyclohexyl-imidazolidine, M.P. 174° - 175°.

from 42.3 g of 1-[p-(2-amino-ethyl)-phenylsulphonyl]-2-imino-3-cyclohexyl-imidazolidine-dihydrochloride and 10.1 g of isopropyl-isothiocyanate the 1-[p-(2-(3-isopropyl-2-thioureido)-ethyl)-phenylsulphonyl]-2-imino-3-cyclohexyl-imidazolidine, M.P. 186° - 187°.

from 42.3 g of 1-[p-(2-amino-ethyl)-phenylsulphonyl]-2-imino-3-cyclohexyl-imidazolidine-dihydrochloride and 9.9 g of cyclopropyl-isothiocyanate the 1-[p-(2-(3-cyclopropyl-2-thioureido)-ethyl)-phenylsulphonyl]-2-imino-3-cyclohexyl-imidazolidine, M.P. 116.5° - 118°.

from 42.3 g of 1-[p-(2-amino-ethyl)-phenylsulphonyl]-2-imino-3-cyclohexyl-imidazolidine-dihydrochloride and 11.5 g of sec.butyl-isothiocyanate the 1-[p-(2-(3-sec.butyl-2-thioureido)-ethyl)-phenylsulphonyl]-2-imino-3-cyclohexyl-imidazolidine, M.P. 186° - 187°.

from 42.3 g of 1-[p-(2-amino-ethyl)-phenylsulphonyl]-2-imino-3-cyclohexyl-imidazolidine-dihydrochloride and 11.5 g of tert.butyl-isothiocyanate the 1-[p-(2-(3-tert.butyl-2-thioureido)-ethyl)-phenylsulphonyl]-2-imino-3-cyclohexyl-imidazolidine, M.P. 201° - 202°.

from 42.3 g of 1-[p-(2-amino-ethyl)-phenylsulphonyl]-2-imino-3-cyclohexyl-imidazolidine-dihydrochloride and 12.9 g of isopentyl-isothiocyanate the 1-[p-(2-(3-isopentyl-2-thioureido)-ethyl)-phenylsulphonyl]-2-imino-3-cyclohexyl-imidazolidine, M.P.

from 42.3 g of 1-[p-(2-amino-ethyl)-phenylsulphonyl]-2-imino-3-cyclohexyl-imidazolidine-dihydrochloride and 14.3 g of n-hexyl-isothiocyanate the 1-[p-(2-(3-n-hexyl-2-thioureido)-ethyl)-phenylsulphonyl]-2-imino-3-cyclohexyl-imidazolidine, M.P. 172.5° - 173°.

from 42.1 g of 1-[p-(2-amino-ethyl)-phenylsulphonyl]-2-imino-3-cyclohexen-3-yl-imidazolidine-dihydrochloride and 11.5 g of n-butyl-isothiocyanate the 1-[p-(2-(3-n-butyl-2-thioureido)-ethyl)-phenylsulphonyl]-2-imino-3-cyclohexen-3-yl-imidazolidine, M.P. 149° - 151°.

from 43.7 g of 1-[p-(2-amino-ethyl)-phenylsulphonyl]-2-imino-3-cyclohexyl-imidazolidine-dihydrochloride and 8.7 g of ethyl-isothiocyanate the 1-[p-(2-(3-ethyl-2-thioureido)-propyl)-phenylsulphonyl]-2-imino-3-cyclohexyl-imidazolidine, M.P. 162° - 163°.

EXAMPLE 14

a. 41.1 g of 1-[p-(2-aminoethyl)-phenylsulphonyl]-2-imino-3-n-butyl-4-methyl-imidazolidine-dihydrochloride are dissolved in 100 ml of water, and

the base is liberated with 150 ml of 2-n sodium hydroxide solution. The base is extracted with 3 times 250 ml of methylene chloride. To the methylene chloride solution (dried with sodium sulphate) are added 8.5 g of n-propylisocyanate, and stirring is maintained for one hour. The reaction mixture is thereupon concentrated in vacuo, and the crystalline residue recrystallized from ethyl acetate. The 1-[p-(2-(3-n-propylureido)-ethyl)-phenylsulphonyl]-2-imino-3-n-butyl-4-methyl-imidazolidine melts at 109°-112°.

b. The starting material: 1-[p-(2-aminoethyl)-phenylsulphonyl]-2-imino-3-butyl-4-methyl-imidazolidine-dihydrochloride is produced by the following process:

An amount of 38.0 g of 1-[p-(2-acetaminoethyl)-phenylsulphonyl]-2-imino-3-butyl-4-methyl-imidazolidine is dissolved in 370 ml of 2-n hydrochloric acid, and the solution is refluxed for 6 hours. The solution is then concentrated to dryness in vacuo, and the obtained oil dissolved in alcohol. The 1-[p-(2-aminoethyl)-phenylsulphonyl]-2-imino-3-butyl-4-methyl-imidazolidine-dihydrochloride, M.P. 240° (decomposition), crystallises out in the cold state.

EXAMPLE 15

Starting with 41.1 g of 1-[p-(2-aminoethyl)-phenylsulphonyl]-2-imino-3-n-butyl-4-methyl-imidazolidine-dihydrochloride are obtained, analogously to Example 14, with 12.5 g of cyclohexylisocyanate, the 1-[p-(2-(3-cyclohexylureido)-ethyl)-phenylsulphonyl]-2-imino-3-n-butyl-4-methyl-imidazolidine, M.P. 137°-138° (from ethyl acetate).

EXAMPLE 16

a. An amount of 41.1 g of 1-[p-(2-aminoethyl)-phenylsulphonyl]-2-imino-3-n-butyl-5-methyl-imidazolidine-dihydrochloride is dissolved in 100 ml of water, and the base liberated with 150 ml of 2-n sodium hydroxide solution. The base is extracted with 3 times 250 ml of methylene chloride. To the methylene chloride solution (dried with sodium sulphate) are added 11.3 g of isoamyl-isocyanate, and stirring is maintained for one hour. The reaction mixture is thereupon concentrated in vacuo, and the crystalline residue recrystallized from ethyl acetate. The 1-[p-(2-(3-isoamyl-ureido)-ethyl) phenylsulphonyl]-2-imino-3-n-butyl-5-methyl-imidazolidine melts at 117°-118°.

b. The starting material: 1-[p-(2-aminoethyl)-phenylsulphonyl]-2-imino-3-butyl-5-methyl-imidazolidine-dihydrochloride is produced, analogously to Example 14 (b), from 38.0 g of 1-[p-(2-acetaminoethyl)-phenylsulphonyl]-2-imino-3-butyl-5-methyl-imidazolidine-dihydrochloride, M.P. 255°-257°.

EXAMPLE 17

39.7 g of 1-[p-(2-aminoethyl)-phenylsulphonyl]-2-imino-3-n-propyl-5-methyl-imidazolidine-dihydrochloride are dissolved in 100 ml of water, and the base is liberated with 150 ml of 2-n sodium hydroxide solution. The base is extracted with 3 times 250 ml of methylene chloride. To the methylene chloride solution (dried with sodium sulphate) are added 11.1 g of cyclopentylisocyanate, and stirring is maintained for one hour. The reaction mixture is thereupon concentrated in vacuo, and the crystalline residue recrystallized from

ethyl acetate. The 1-[p-(2-(3-cyclopentylureido)-ethyl)-phenylsulphonyl]-2-imino-3-n-propyl-5-methyl-imidazolidine melts at 137°-138°.

The starting material: 1-[p-(2-aminoethyl)-benzenesulphonyl]-2-imino-3-propyl-5-methyl-imidazolidine-dihydrochloride is produced as follows:

An amount of 36.6 g of 1-[p-(2-acetaminoethyl)-phenylsulphonyl]-2-imino-3-propyl-5-methyl-imidazolidine is dissolved in 370 ml of 2-n hydrochloric acid, and the solution is refluxed for 6 hours. The solution is then concentrated to dryness in vacuo, and the obtained oil dissolved in alcohol. The 1-[p-(2-aminoethyl)-benzenesulphonyl]-2-imino-3-propyl-5-methyl-imidazolidine-dihydrochloride, M.P. 241°-242°, crystallises out in the cold state.

EXAMPLE 18

39.8 g of 1-[p-(2-aminoethyl)-phenylsulphonyl]-2-imino-3-n-propyl-5-methyl-imidazolidine-dihydrochloride are dissolved in 100 ml of water, and the base is liberated with 150 ml of 2-n sodium hydroxide solution. It is extracted with 3 times 250 ml of methylene chloride. To the methylene chloride solution (dried with sodium sulphate) are added 12.5 g of cyclohexyl-isocyanate, and stirring is maintained for 1 hour. The reaction mixture is thereupon concentrated in vacuo, and the crystalline residue recrystallized from ethyl acetate. The 1-[p-(2-(3-cyclohexylureido)-ethyl)-phenylsulphonyl]-2-imino-3-n-propyl-5-methyl-imidazolidine melts at 99.5°-100.5°.

The starting material: 1-[p-(2-aminoethyl)-phenylsulphonyl]-2-imino-3-n-propyl-5-methyl-imidazolidine-dihydrochloride is produced analogously to Example 17.

EXAMPLE 19

a. 39.8 g of 1-[p-(2-aminoethyl)-phenylsulphonyl]-2-imino-3-n-butyl-imidazolidine-dihydrochloride are dissolved in 100 ml of water, and the base is liberated with 150 ml of 2-n sodium hydroxide solution. It is extracted with 3 times 250 ml of methylene chloride. To the methylene chloride solution (dried with sodium sulphate) are added 14 g of 4-cyclohex-3-enylisothiocyanate, and stirring is maintained for 1 hour. The reaction mixture is thereupon concentrated in vacuo, and the crystalline residue recrystallized from ethyl acetate. The 1-[p-(2-(3-cyclohex-3-enyl-2-thioureido)-ethyl)-phenylsulphonyl]-2-imino-3-n-butyl-imidazolidine melts at 182°-183°.

b. The starting material: 1-[p-(2-aminoethyl)-phenylsulphonyl]-2-imino-3-n-butyl-imidazolidine-dihydrochloride is obtained according to the instructions given in Example 1(b).

EXAMPLE 20

39.8 g of 1-[p-(2-aminoethyl)-phenylsulphonyl]-2-imino-3-isobutyl-imidazolidine-dihydrochloride are dissolved in 100 ml of water, and the base is liberated with 150 ml of 2-n sodium hydroxide solution. It is extracted with 3 times 250 ml of methylene chloride. To the methylene chloride solution (dried with sodium sulphate) are added 9.9 g of n-butylisocyanate, and stirring is maintained for 1 hour. The reaction mixture is thereupon concentrated in vacuo, and the crystalline

residue recrystallized from ethyl acetate. The 1-[p-(2-(3-nbutylureido)-ethyl)-phenylsulphonyl]-2-imino-3-isobutyl-imidazolidine melts at 144°–144.5°.

The starting material: 1-[p-(2-aminoethyl)-phenylsulphonyl]-2-imino-3-isobutyl-imidazolidine-dihydrochloride is produced analogously to Example 5(b).

EXAMPLE 21

a. 41.0 g of 1-[p-(2-aminoethyl)-phenylsulphonyl]-2-imino-3-cyclopentyl-imidazolidine-dihydrochloride are dissolved in 100 ml of water, and the base is liberated with 150 ml of 2-n sodium hydroxide solution. It is extracted with 3 times 250 ml of methylene chloride. To the methylene chloride solution (dried with sodium sulphate) are added 14.1 g of cyclohexylisothiocyanate, and stirring is maintained for 1 hour. The reaction mixture is thereupon concentrated in vacuo, and the crystalline residue recrystallized from ethyl acetate. The 1-[p-(2-(3-cyclohexyl-2-thioureido)-ethyl)-phenylsulphonyl]-2-imino-3-cyclopentyl-imidazolidine melts at 215°–216°.

b. The starting material: 1-[p-(2-aminoethyl)-phenylsulphonyl]-2-imino-3-cyclopentyl-imidazolidine-dihydrochloride is obtained according to the instructions given in Example 7(b).

EXAMPLE 22

a. 42.4 g of 1-[p-(2-aminoethyl)-phenylsulphonyl]-2-imino-3-cyclohexyl-imidazolidine-dihydrochloride are dissolved in 100 ml of water, and the base is liberated with 150 ml of 2-n sodium hydroxide solution. It is extracted with 3 times 250 ml of methylene chloride. To the methylene chloride solution (dried with sodium sulphate) are added 12.7 g of cyclopentylisothiocyanate, and stirring is maintained for one hour. The reaction mixture is thereupon concentrated in vacuo, and the crystalline residue recrystallized from ethyl acetate. The 1-[p-(2-(3-cyclopentyl-2-thioureido)-ethyl)-phenylsulphonyl]-2-imino-3-cyclohexyl-imidazolidine melts at 206°–207°.

b. The starting material: 1-[p-(2-aminoethyl)-phenylsulphonyl]-2-imino-3-cyclohexyl-imidazolidine-dihydrochloride is obtained according to the instructions given in Example 9(b).

EXAMPLE 23

Starting with 42.4 g of 1-[p-(2-aminoethyl)-phenylsulphonyl]-2-imino-3-cyclohexyl-imidazolidine-dihydrochloride are obtained, analogously to Example 22, the following:

a. with 14 g of cyclohex-3-enyl-isothiocyanate, 1-[p-(2-(3-cyclohex-3-enyl-2-thioureido)-ethyl)-phenylsulphonyl]-2-imino-3-cyclohexyl-imidazolidine, M.P. 208.5°–209.5° (from ethyl acetate).

b. with 14 g of cyclohexylisothiocyanate, 1-[p-(2-(3-cyclohexyl-2-thioureido)-ethyl)-phenylsulphonyl]-2-imino-3-cyclohexyl-imidazolidine, M.P. 214°–215° (from ethyl acetate).

EXAMPLE 24

a. 39.8 g of 1-[p-(2-aminoethyl)-phenylsulphonyl]-2-imino-3-n-butyl-imidazolidine-dihydrochloride are dissolved in 100 ml of water, and the base is liberated

with 150 ml of 2-n sodium hydroxide solution. It is extracted with 3 times 250 ml of methylene chloride. To the methylene chloride solution (dried with sodium sulphate) are added 20 g of triethylamine. At room temperature are then added the solution of 23.2 g of diphenylcarbamic acid chloride in 100 ml of methylene chloride, and stirring is maintained for 4 hours at room temperature. The whole is then washed twice with 30 ml of water each time. The aqueous phases are extracted twice with 100 ml of methylene chloride. The combined methylene chloride phases yield, after being dried with sodium sulphate, filtered, and concentrated by evaporation, 1-[p-(2-(3,3-diphenyl-ureido)-ethyl)-phenylsulphonyl]-2-imino-3-n-butyl-imidazolidine which, recrystallized from ethyl acetate, melts at 96.5°–98°.

b. The starting material: 1-[p-(2-aminoethyl)-phenylsulphonyl]-2-imino-3-n-butyl-imidazolidine-dihydrochloride is obtained according to the instructions given in Example 1(b).

EXAMPLE 25

a. 39.8 g of 1-[p-(2-aminoethyl)-phenylsulphonyl]-2-imino-3-n-butyl-imidazolidine-dihydrochloride are dissolved in 100 ml of water, and the base is liberated with 150 ml of 2-n sodium hydroxide solution. The base is extracted with 3 times 250 ml of methylene chloride. To the methylene chloride solution (dried with sodium sulphate) are added 20 g of triethylamine. At room temperature is then added dropwise the solution of 14.8 g. of piperidine carbonyl chloride in 100 ml of methylene chloride, and the whole is stirred for 4 hours at room temperature; it is then washed twice with 30 ml of water each time. The aqueous phases are extracted twice with 100 ml of methylene chloride. The combined methylene chloride phases yield, after drying with sodium sulphate, filtration, and concentration by evaporation, 1-[p-(2-(1-piperidinocarboxamido)-ethyl)-phenylsulphonyl]-2-imino-3-n-butyl-imidazolidine which, recrystallized from ethyl acetate, melts at 179.5°–180.5°.

b. The starting material: 1-[p-(2-aminoethyl)-phenylsulphonyl]-2-imino-3-n-butyl-imidazolidine-dihydrochloride is obtained according to the instructions given in Example 1(b).

EXAMPLE 26

a. 39.8 g of 1-[p-(2-aminoethyl)-phenylsulphonyl]-2-imino-3-isobutyl-imidazolidine dihydrochloride are dissolved in 100 ml of water, and the base is liberated with 150 ml of 2-n sodium hydroxide solution. The base is extracted with 3 times 250 ml of methylene chloride. To the methylene chloride solution (dried with sodium sulphate) are added 20 g of triethylamine. At room temperature are then added the solution of 9.8 g of dimethylcarbamic acid chloride in 100 ml of methylene chloride, and the whole is stirred for 4 hours at room temperature; it is then washed twice with 30 ml of water each time. The aqueous phases are extracted twice with 100 ml of methylene chloride. The combined methylene chloride phases yield, after being dried with sodium sulphate, filtered, and concentrated by evaporation, 1-[p-(2-(3,3-dimethylureido)-ethyl)-phenylsulphonyl]-2-imino-3-isobutyl-imidazolidine which, recrystallized from ethyl acetate, melts at 132°–135°.

b. The starting material: 1-[p-(2-aminoethyl)-phenylsulphonyl]-2-imino-3-isobutyl-imidazolidine-dihydrochloride is obtained according to the instructions given in Example 5(b).

EXAMPLE 27

Analogously to Example 28 are obtained: from 39.6 g of 1-[p-(2-amino-ethyl)-phenylsulphonyl]-2-imino-3-n-butyl-imidazolidine-dihydrochloride and 15.0 g of 4-morpholinecar-bonylchloride the 1-[p-(2-(4-morpholinecarboxamido) ethyl)-phenylsulphonyl]-2-imino-3-n-butyl-imidazolidine, M.P. 176° - 177°. from 42.5 g of 1-[p-(2-amino-ethyl)-phenylsulphonyl]-2-imino-3-cyclohexyl-imidazolidine-dihydrochloride and 13.9 g of N-n-butyl-N-methylcarbamic acid chloride the 1-[p-(2-(3-n-butyl-13-methylureido)-ethyl)-phenylsulphonyl]-2-imino-3-cyclohexyl-imidazolidine, M.P. 134° - 136°. from 39.6 g of 1-[p-(2-amino-ethyl)-phenylsulphonyl]-2-imino-3-n-butyl-imidazolidine-dihydrochloride and 13.9 g of N-n-butyl-N-methyl-amino-carbonylchloride the 1-[p-(2-(3,3-n-butyl-methylureido)-ethyl)-phenylsulphonyl]-2-imino-3-n-butyl-imidazolidine, M.P. 136° - 137°.

EXAMPLE 28

a. 41.0 g of 1-[p-(2-aminoethyl)-phenylsulphonyl]-2-imino-3-cyclopentyl-imidazolidine-dihydrochloride are dissolved in 100 ml of water, and the base is liberated with 150 ml of 2-n sodium hydroxide solution. The base is extracted with 3 times 250 ml of methylene chloride. To the methylene chloride solution (dried with sodium sulphate) is added dropwise, at room temperature, the solution of 23.2 g of diphenylcarbamic acid chloride in 100 ml of methylene chloride; the whole is then stirred for 4 hours at room temperature, and afterwards washed twice with 30 ml of water each time. The aqueous phase is extracted twice with 100 ml of methylene chloride. The combined methylene chloride phases yield, after being dried with sodium sulphate, filtered, and concentrated by evaporation, 1-[p-(2-(3,3-diphenylureido)-ethyl)-phenylsulphonyl]-2-imino-3-cyclopentyl-imidazolidine-hydrochloride which, recrystallized from ethyl acetate, melts at 209°-210°.

b. The starting material: 1-[p-(2-aminoethyl)-phenylsulphonyl]-2-imino-3-cyclopentyl-imidazolidine-dihydrochloride is obtained according to the instructions given in Example 7(b).

EXAMPLE 29

39.7 g of 1-[p-(2-aminoethyl)-phenylsulphonyl]-2-imino-3-n-butyl-imidazolidine-dihydrochloride are dissolved in 100 ml of water, and the base is liberated with 150 ml of 2-n sodium hydroxide solution. The base is extracted with 3 times 250 ml of methylene chloride. To the methylene chloride solution (dried with sodium sulphate) are added 20 g of triethylamine. At room temperature is then added the solution of 15 g of 4-morpholinyl-chloride in 100 ml of methylene chloride, and stirring is maintained for 4 hours at room temperature; the whole is then washed twice with 30 ml of water each time. The aqueous phases are extracted twice with 100 ml of methylene chloride. The combined methylene chloride phases yield, after drying

with sodium sulphate, filtration, and concentration by evaporation, 1-[p-(2-(4-morpholine carboxamido)-ethyl)-phenylsulphonyl]-2-imino-3-n-butyl-imidazolidine which, recrystallized from ethyl acetate, melts at 176°-177°.

The starting material: 1-[p-(2-aminoethyl)-phenylsulphonyl]-2-imino-3-n-butyl-imidazolidine-dihydrochloride is obtained according to the instructions given in Example 1(b).

EXAMPLE 30

5 g of 1-[p-(2-(3-ethyl-2-thioureido)-ethyl)-phenylsulphonyl]-2-imino-3-cyclopentyl-imidazolidine, M.P. 178°, are dissolved in 100 ml of 2-n. hydrochloric acid, while slightly heating. After cooling with ice-water the 1-[p-(2-(3-ethyl-2-thioureido)-ethyl)-phenylsulphonyl]-2-imino-3-cyclopentyl-imidazolidine-hydrochloride precipitates, M.P. 166° - 168°.

The following prescriptions further illustrate the production of tablets and drages:

EXAMPLE 31

1,000 g of 1-[p-(2-(3-butylureido)-ethyl)-phenylsulphonyl]-2-imino-3-cyclohexyl-imidazolidine are mixed with 500 g of lactose and 270 g of potato starch; the mixture is then moistened with an aqueous solution of 8.0 g of gelatine, and granulated through a sieve. After drying of the granulate, 60.0 g of potato starch 30 60.0 g of talcum, 10.0 g of magnesium stearate and 20.0 g of colloidal silicon dioxide are mixed in; and the mixture is pressed into 10,000 tablets each weighing 200 mg and each containing 100 mg of active substance. Optionally, the tablets may be provided with grooves for more precise adjustment of the dosage amount.

EXAMPLE 32

40 A granulate is prepared from 1,000 g of 1-[p-(2-(3-butyl-thio-ureido)-ethyl)-phenylsulphonyl]-2-imino-3-cyclohexyl-imidazolidine, 345.0 g of lactose and the aqueous solution of 6.0 g of gelatine. After drying, the granulate is mixed with 10.0 g of colloidal silicon dioxide, 45 40.0 g of talcum, 40.0 g of potato starch and 5.0 g of magnesium stearate; the mixture is then pressed into 10,000 dragee cores. These are subsequently coated with a concentrated syrup made from 533.0 g of crystallized saccharose, 20.0 g of shellac, 75.0 g of gum arabic, 250 g of talcum, 20 g of colloidal silicon dioxide and 1.5 g of dyestuff; and then dried. The obtained dragees each weigh 240 mg and each contain 100 mg of active substance.

What is claimed is:

1. A compound of the formula I,

wherein

R₁ is alkyl of one to six carbon atoms, allyl, cycloalkyl of five to eight carbon atoms or cycloalkenyl of five to eight carbon atoms;

R₂ is hydrogen, ethyl or methyl;

R_3 is alkyl of one to six carbon atoms, cycloalkyl of at most eight carbon atoms, cycloalkenyl of at most eight carbon atoms, alkenyl of three to five carbon atoms or phenyl;

R_4 is hydrogen, alkyl of one to six carbon atoms or phenyl; and

R_3 and R_4 together are a polymethylene chain of four to seven carbon atoms or morpholino;

X is oxygen or sulfur; and

m is 2 or 3; or a pharmaceutically acceptable acid addition salt thereof.

2. A compound according to claim 1, which is 1-[p-(2-(3-n-butyl-2-thioureido)-ethyl)-phenylsulfonyl]-2-imino-3-n-butyl-imidazolidine.

3. A compound according to claim 1, which is 1-[p-(2-(3-n-butylureido)-ethyl)-phenylsulfonyl]-2-imino-3-cyclohexyl-imidazolidine.

4. A compound according to claim 1, which is 1-[p-(2-(3-n-butyl-2-thioureido)-ethyl)-phenylsulfonyl]-2-imino-3-cyclohexyl-imidazolidine.

5. A compound according to claim 1, which is 1-[p-(2-(3-n-propylureido)-ethyl)-phenylsulfonyl]-2-imino-3-(4-methylcyclohexyl)-imidazolidine.

6. A compound according to claim 1, which is 1-[p-(2-(3-ethyl-2-thioureido)-ethyl)-phenylsulfonyl]-2-imino-3-cyclopentylimidazolidine.
